US0D1063754S

(12) **United States Design Patent** (10) **Patent No.:** **US D1,063,754 S**
(45) **Date of Patent:** **** Feb. 25, 2025**

(54) **CONTROL AND INDICATOR PANEL FOR MOTOR VEHICLE**

(71) Applicant: **Dr. Ing. h.c. F. Porsche Aktiengesellschaft**, Stuttgart (DE)

(72) Inventor: **Tarek Ashour**, Stuttgart (DE)

(73) Assignee: **Dr. Ing. h.c. F. Porsche Aktiengesellschaft** (DE)

(**) Term: **15 Years**

(21) Appl. No.: **29/915,039**

(22) Filed: **Oct. 25, 2023**

(30) **Foreign Application Priority Data**

Jun. 5, 2023 (EM) 015023695-0010

(51) **LOC (15) Cl.** **12-16**

(52) **U.S. Cl.**

USPC **D12/192**

(58) **Field of Classification Search**

USPC D20/35, 39; D12/190, 192, 195, 415, D12/419

CPC B60K 37/10; B60Q 3/225; B60Q 3/64; B60Q 3/10; B60N 3/10; B60R 13/02; B60R 13/0262; B62D 25/14
